[57] CLAIM

The ornamental design for a wastebasket hanger, as shown and described.

DESCRIPTION

FIG. 1 is a perspective view of the ornamental wastebasket hanger.

FIG. 2 is a rear view of the ornamental wastebasket hanger.

FIG. 3 is an end view of the ornamental view of the wastebasket hanger showing the edge of a wastebasket attached thereto as well as the wall or door attached thereto, said attached wastebasket and wall or door shown only for illustrative purposes only.
